UNITED STATES PATENT OFFICE.

FRANZ OBRIKAT, JR., OF LOS ANGELES, CALIFORNIA.

PATTERN FILE.

Application filed July 18, 1921. Serial No. 485,527.

To all whom it may concern:

Be it known that I, FRANZ OBRIKAT, Jr., a citizen of the United States, residing at Los Angeles, in the county of Los Angeles and State of California, have invented new and useful Improvements in Pattern Files, of which the following is a specification.

This invention relates to a device for filing sheet articles, and particularly pertains 10 to a bracket or hanger for supporting patterns, such as are formed of paper or other sheet material.

An object of this invention is to provide a device which is especially applicable for 15 use in the filing of patterns employed by furriers, garment workers, and the like, by means of which a large number of patterns may be hung on one support, and any one of the patterns selected and removed without 20 taking any other patterns from the support.

Another object is to provide a pattern hanger which is simple in construction and adapted to be economically manufactured, and which is strong and durable.

25 With the foregoing objects in view, as well as any other objects or advantages as may subsequently appear, my invention consists in the construction and arrangement of parts hereinafter set forth and claimed, 30 and illustrated in the accompanying drawings, in which:

Figure 1 is a perspective view of the pattern file, showing it in its preferred embodiment.

35 Figure 2 is a perspective view illustrating the manner of mounting the patterns on the file and showing how a pattern may be removed from between adjacent patterns without detaching other patterns from the 40 file.

Figure 3 is a detail in section showing the manner of constructing the supporting bracket and showing how a separable pin is carried by the bracket.

45 Referring to the drawings more specifically, 5 indicates a back plate which is adapted to be secured to a support, such as a wall or panel, by means of screws 7 or other suitable fastenings. The back plate is 50 formed with an outwardly extending portion 8 at its upper end terminating in a downturned end portion 9 spaced forward of the back plate and constituting with the

latter a support for a tube 10 which passes through an opening 11 in the end portion 9 and is rigidly engaged in an opening 12 in the back plate 5. The tube is thus fastened at its inner end and supported at a point spaced from its inner end so as to be securely held in place, and whereby the tube 60 is adapted to carry considerable weight without danger of being detached from its support.

The tube is disposed on its support to extend upwardly therefrom at an inclination 65 and its outer end face extends diagonally to form the terminus of the tube with a point 13 and with an upwardly extending elongated opening 14. The tube is designed to receive a demountable pin 15 comprising 70 a shank 16 fitted at its outer end with a head 17 and tapered at its inner end to form a point 18.

In the application and operation of the invention, the patterns or sheets 19 to be 75 placed on the file may be engaged with the latter either by threading them on the tube 10 or the pin 15; the pin being removed for this purpose. The pin is then inserted in the open outer end of the tube and the patterns strung on the tube 10.

When it is desired to remove a pattern from between adjacent patterns, the outermost patterns are moved on to the pin, as 85 shown in Figure 2, and the pin is removed so that the end pattern then exposed either on the pin or the tube may be removed without disengaging other of the patterns. The pin carrying the patterns will then be reinserted in the tube and the patterns transferred from the pin to the tube. 90

I claim:

1. In a device for filing sheet articles, a back plate having an outwardly and downwardly extending upper end portion formed 95 with the outwardly extending portion spaced from the back plate; said downwardly extending portion formed with an opening, a tube having its inner end engaged with the back plate; said tube extending through the opening and having an open outer end, and a pin insertable in and removable from the outer end of said tube.

2. In a device for filing sheet articles, a back plate having an outwardly and downwardly extending upper end portion formed 100

105

with the outwardly extending portion spaced from the back plate; said downwardly extending portion formed with an opening, a tube having its inner end engaged with the back plate; said tube extending upwardly at an inclination from the back plate.

3. In a device for filing sheet articles, a back plate, an upwardly inclined tube carried by said back plate opening at its outer end, a brace for the tube, and a pin insertable in and removable from said tube.

FRANZ OBIKAT, JR.
